TOY PORPOISE

Charles K. Grieder, 700 S. Lyon,
Santa Ana, Calif. 92705

Filed Nov. 15, 1971, Ser. No. 199,090

Term of patent 14 years

Int. Cl. D21—01
U.S. Cl. D34—15 B

FIG. 1

FIG. 2

FIG. 3

FIG. 4

FIG. 5

FIG. 1 is an elevational side view of a toy porpoise according to my present design;

FIG. 2 is a bottom plan view of the toy of FIG. 1;

FIG. 3 is a top plan view of the toy showing my present design;

FIG. 4 is a front elevational view thereof; and

FIG. 5 is a rear elevational view of such toy showing my present design.

I claim:

The ornamental design for a toy porpoise, substantially as shown and described.
